UNITED STATES PATENT OFFICE.

RICHARD J. SCHWEITZER, OF CHICAGO, ILLINOIS.

SOIL-STACK CONNECTION.

1,095,291.

Specification of Letters Patent.

Patented May 5, 1914.

Application filed April 16, 1912. Serial No. 691,176.

To all whom it may concern:

Be it known that I, RICHARD J. SCHWEITZER, a citizen of the United States, residing at Chicago, in the county of Cook and State of Illinois, have invented certain new and useful Improvements in Soil-Stack Connections, of which the following is a specification.

The present invention relates to a form of pipe used for the purpose of connecting a toilet fixture with a soil-stack, and said connection is of a form to enable a sealed joint to be provided to prevent leakage of gas at the juncture of the connecting pipe with the fixture.

The objects of the present invention are to provide a connecting pipe of a nature which will permit it to lie in relatively close relation to the floor, so that it may be interposed in a relatively shallow space between the floor and ceiling; and to so configurate the pipe as to obtain the same cross-sectional area throughout the interior bore thereof.

A further object of the invention is to render the connection adjustable as to length, and to so arrange the chamber which receives the sealing substance as to enable the sealing substance to act as a cementative to adhere the pipe and connection together.

The invention further consists in the features of construction and in the combination of parts hereinafter described and claimed.

In the drawings, Figure 1 is a longitudinal section of the connection of the present invention in operative position; Fig. 2, a sectional detail of the thimble of the present invention; Fig. 3, a view showing the pipe and thimble in engagement, with the pipe tilted at an angle; Fig. 4, an elevation of the connecting pipe of the present invention; Fig. 5, a plan view of said pipe; Fig. 6, a section on line 6—6 of Fig. 5, looking in the direction of the arrow; and Fig. 7, a detail of the connection between the thimble and fixture.

In the art to which the present invention relates, it is necessary to form a calked joint or sealed connection at the juncture of the connecting pipe leading from the soil-stack and the toilet fixture. This is to prevent the escapement of gas or liquid at the juncture of said connecting pipe and fixture. It is considered more expedient in practice to form this calked joint prior to the installation of the fixture, in order to determine

more accurately whether the joint is sufficiently gas and water tight.

It is one of the objects of the present invention to so arrange the well which receives the sealing substance that it will be possible for the mechanic to calk this joint prior to the installation of the fixture; that is, he can first set what may be termed the foundation for the fixture, and then perform the calking operation necessary to make the tight joint between this foundation and the fixture. And he can further easily determine before setting the fixture whether the seal is perfect or not by reason of the fact that it is fully visible while being formed. A further difficulty which is experienced in the connecting of fixtures to soil-stacks lies in the fact that in some instances a relatively shallow space is provided between the floor and the ceiling, and the pipe connecting the soil-stack and the fixture therefore must lie, when inserted, relatively close to the floor line in order to accommodate itself within the space allowed. The device of the present invention is designed with a view to overcoming these difficulties, and in the form shown in the drawings is as follows:

Referring particularly to Fig. 1, the device is illustrated as consisting of a pipe 8, which is of elbow formation, and terminates at one end in a relatively short upwardly extending neck 9. At the point where the neck and body of the pipe come together, said pipe has its upper wall depressed as indicated at 10. By this arrangement, the upper end of the neck lies in close relation to the upper surface of the pipe 8, reducing the transverse dimension of the joined pipe and neck and enabling the pipe to be positioned in a shallow space, and at the same time giving the desired length to the neck. By this arrangement should the system be installed in a building where the space between the floor and the ceiling beneath is shallow, no difficulty will be experienced in installing the pipes in this space, by reason of its compact formation. By depressing the pipe as indicated at the point 10, the dimensions of the pipe will be contracted in one direction at this point. It is not desirable to have a contraction of this nature, which will restrict the area of the pipe at this point, as such a restriction would tend to increase the danger of the pipe choking if an unusual heavy flow were passed therethrough. Therefore, in order to maintain

the same cross-sectional area throughout the pipe and prevent such a point of congestion, the pipe is broadened out at the sides thereof, as indicated by the numeral 11 in Figs. 5 and 6, which counteracts the contraction caused by the indenting of the upper wall.

Adjacent to the point where the neck and body of the pipe meet, a screw-thread 12 is cast upon the outer surface of said neck. 10 This thread is adapted to receive and mesh with a cast thread 13 formed on the inner face of the lower end of a collar 14. Said collar is provided with a flange 15 adapted to rest upon the upper face of the flooring 15 which is indicated by the numeral 16. The flange is provided with a series of radial slots 17, which receive locking members 18, which serve to join said collar to a fixture 19 in a manner clearly understood by referring to Fig. 7.

The provision of the cast threads 12 and 13 enables many desirable functions to be accomplished: It permits of an adjustment of the collar 14 with respect to the floor line, so that said collar can be positioned to rest squarely and securely upon the floor, irrespective of the position of the pipe 8 below the floor. Furthermore, the threads act as spacing members to separate the inner 25 wall of the collar away from the outer wall of the neck for the entire distance above the termination of the screw-threads, where these surfaces are adjoining. This provides a chamber 20 between the pipe and thimble, 30 into which suitable sealing substance 21 can be tamped. Such sealing substance acts as a preventive against leakage of gas or other substance at the point of connection of the neck and collar, and further serves as a cementative agency for joining the collar and neck together in a secure and staple manner.

By utilizing cast threads, a considerable amount of play is allowed between the meshing threaded surfaces, which permits the flange of the collar to adjust itself to lie flat upon the floor in case the pipe is not 45 extending parallel with the floor. This feature will be clearly understood from a study of Fig. 3. And the character of said threads 50 also allows the sealing substance to filter or work its way in between the meshing portions of the thimble and pipe, effecting the cementing action above referred to. By connecting the thimble and pipe in this manner, said connection can be made and the sealing substance placed in the chamber 20 prior to the setting of the fixture. This 55 allows the tamping operation to be easily and readily accomplished, since the chamber 60 20 is readily accessible to the workmen, inasmuch as it is brought very close to the floor line. This is a very desirable feature in devices of this kind, since it enables the seal to be more easily and efficiently made, 65 and also enables the workman to see the

nature of the seal which has been produced, so that he can determine whether or not it is a good one. If the seal is made under conditions where it cannot be observed in the process of formation, bubbles and other 70 deformities are sometimes present and pass unnoticed, but which later render the seal defective and permit the escapement of gas when the system is put into operation.

The device of the present invention is 75 extremely cheap and simple of construction, consisting as it does solely of two parts: the pipe with the neck joined thereto, and the thimble. All portions of the device are produced by a casting operation and no machine 80 work of any kind or description is necessary to produce the completed article, ready for use. The upper end of the thimble is provided with a concave flange 22, which receives a ring of packing material 23^a that 85 forms an additional preventive against the escapement of gas around the floor line and around the juncture of the pipe and thimble. The flange 22 is, however, of a relatively shallow nature, so as not to block or cover 90 the entrance to the chamber 20. The outlet 23 from the fixture extends below the upper edge of the neck, so that a continuous and unbroken passage for fluid is provided.

As shown in Figs. 1 and 3, the neck of the 95 pipe 8 is provided with an interior thread 25, which is adapted to receive a plug 26. These features provide means whereby the system can be tested prior to the installation 100 of the fixture. That is, by inserting the plug in the manner shown in Fig. 3, a volume of water can be passed through the piping to determine the effectiveness of the connections, the plug acting as a means to prevent the water from squirting through the open 105 end of the neck.

By the arrangement of cast threads shown and described, a relatively long seal can be produced at the juncture of the pipe and thimble, thus forming an efficient preventive 110 against the escapement of gas at this point.

I claim:

1. A soil stack connection consisting solely of an integral pipe bent at one end to provide a neck and an integral thimble adapted to rest upon the floor of the structure, means for joining the thimble to a toilet fixture, the lower end of said thimble extending below the upper end of the neck, a cast thread on a portion of the exterior of the neck, a cast 115 thread on a portion of the interior of the thimble, said threads meshing loosely and serving as the means for preventing lateral displacement between the thimble and neck and for allowing angular adjustment between the thimble and pipe, said loosely meshing threads spacing the thimble and neck apart between said threads and the upper end of the neck which space constitutes a chamber for sealing substances, said 120 125 130

- pipe having its top surface indented at the point of juncture of the neck and the body of the pipe whereby the distance between the upper edge of the neck and the upper 5 wall of the pipe is increased, and the distance between the upper edge of the neck and the lower wall of the pipe is decreased, said pipe having another wall thereof expanded at said point of juncture whereby the same 10 cross sectional area is maintained throughout the pipe, substantially as described.
2. A soil stack connection consisting solely of an integral pipe bent at one end to provide a neck and an integral thimble adapted 15 to rest against the floor of the structure, said thimble having its lower end extending below the upper end of the neck, loosely interlocking means for joining said thimble and neck together forming the sole means 20 for preventing lateral displacement of said neck from said thimble and for permitting angular adjustment therebetween, said thimble and pipe being spaced apart by said interlocking means to provide a chamber for 25 sealing substances between the thimble and neck, said pipe having its top surface indented at the juncture of the pipe and neck to decrease the distance between the top of the neck and the bottom face of the pipe 30 and increase the distance between the top of the neck and the upper face of the pipe and having another wall expanded at said point of juncture whereby the same cross sectional area is maintained throughout the pipe, substantially as described.
3. A soil stack connection comprising an integral pipe bent at one end to provide a neck, the upper face of said pipe being depressed at the juncture of the neck and body 35 whereby the distance between the upper end of the neck and the lower edge of the pipe is decreased and the distance between the upper 40 edge of the neck and the upper edge of the pipe increased and another face of said pipe being expanded at said point of juncture whereby the same cross sectional area is maintained throughout the pipe, an exterior cast thread on the lower end of said neck, the thimble being provided with a flange adapted to rest against the floor of the structure, means for securing said thimble and fixture together, an interior cast thread on the lower end of said thimble, said threads on the thimble and neck loosely intermeshing whereby they prevent lateral separation of said thimble from said neck and afford a bearing to permit angular adjustment between said pipe and thimble, said loosely meshing thread providing a space extending from the thread to the upper end 45 of the neck, said space constituting a well for sealing substances, substantially as described.
4. A soil stack connection comprising an angular bend producing a neck, an exterior cast thread on said neck extending a portion of the way thereof, a thimble provided with a flange adapted to be secured to the toilet fixture and to rest against the floor of the structure, an interior cast thread on the 50 thimble extending a portion of the way thereof, said threads loosely intermeshing whereby separation of said thimble and bend is prevented and a pivotal bearing afforded to permit angular movement between said thimble and bend and said loosely intermeshing threads forming a space between said thimble and neck constituting a well for sealing substances, substantially as described.
